UNITED STATES PATENT OFFICE.

GEORGE M. BEARDSLEE, OF CHICAGO, ILLINOIS, ASSIGNOR TO BEARDSLEE CHANDELIER MANUFACTURING COMPANY, A CORPORATION OF DELAWARE.

LIGHTING-FIXTURE.

1,239,556.

Specification of Letters Patent. Patented Sept. 11, 1917.

Application filed March 20, 1916. Serial No. 85,268.

To all whom it may concern:

Be it known that I, GEORGE M. BEARDSLEE, a citizen of the United States, and resident of Chicago, in the county of Cook and State 5 of Illinois, have invented certain new and useful Improvements in Lighting-Fixtures, of which the following is a description, reference being had to the accompanying drawing, which forms a part of my specification.

10 My invention relates to a lighting fixture more especially intended for commercial and industrial purposes, which, for example, may employ the 500 watt lamp known as the new type "C" or nitrogen gas-filled lamp, and has for its object the provision of a unit more particularly adapted for semi-direct or indirect lighting, permitting the use of a lamp of the character mentioned, which, however, could not otherwise 15 be employed because of its excessive brilliancy; the invention providing fixture elements which may also be employed in connection with direct lighting units.

A further object of the invention is the 20 provision of a fixture or unit wherein the respective elements comprising the fixture or unit are so constructed and arranged that when employed especially for semi-direct lighting, the unsightly shadows usually 25 encountered with semi-direct lighting fixtures, as heretofore employed, will be entirely eliminated; at the same time providing a construction wherein the rays of light will be so refracted and also reflected that a general or uniform diffusion of light will be obtained on all sides of the fixture.

The invention contemplates a lighting 30 unit which will be substantially dust and insect proof, and yet at the same time enable proper ventilation being obtained intermediate of the respective elements constituting the unit; the invention providing a lighting fixture or unit which may be easily assembled or dismantled, and one which is comparatively inexpensive in manufacture.

40 The advantages and objects of my invention will be more fully comprehended from the following detailed description of the accompanying drawing, wherein:—

45 Figure 1 is a partial side elevation and partial central sectional view of my improved fixture.

50 Fig. 2 is a detail bottom plan view of the upper or metallic portions of the fixture, to-

wit of the holder and lamp-socket of the 55 fixture; in other words, with the translucent members and the lamp of the unit removed.

Fig. 3 is a vertical sectional view of the top member or husk and the reflector-holder with the socket and reflector-holding yoke 60 or member shown in section and side elevation; the figure illustrating a modified form of the invention.

Fig. 4 is a partial sectional and perspective view of another modified form of holder 65 or yoke for holding the lamp-socket, reflector and the translucent reflector or shade-holder.

In the particular exemplification of the invention, it is shown in Fig. 1 in the nature 70 of a lighting unit known as a semi-direct fixture, comprising a top attaching cap 10, of suitable material; the cap 10, illustrated in Fig. 1, being of cast metal and provided with the screw-receiving portions or lugs 11 75 and 12. The cap 10, in the construction shown in Fig. 1, is provided with a tapped opening 13, which may receive any suitable means for securing or suspending the lighting fixture or unit in place; the fixture or 80 unit being especially intended to be suspended from ceilings and the like by any suitable means, as, for example, loops or ring-plugs of the construction shown.

The cap 10 receives the socket-member or 85 lamp-holder 14, to which the electric wires or conductors are secured; the socket 14 being of the usual non-conducting material, such as porcelain and the like. The lead wires are adapted to extend through the 90 tapped opening 13 and through the suspending or attaching means screwed into the tapped opening in the cap 10. The socket 14 is shown secured to the cap 10 by means of suitable screws 15 which take into the portion or lugs 11 in the upper part of the cap. The socket or holder 14 receives the lamp 16 95 in the usual manner.

Removably secured to the portions or lugs 12 of top cap 10 is a reflector or globe holder 100 17; the holder being secured to the lugs 12 of cap 10 by means of suitable screws 18. The lugs 12, like lugs 11, are preferably disposed at diametrically opposite points so as to leave intervening spaces between the lugs, 105 as is evident from the bottom plan view illustrated in Fig. 2, thus permitting a circulation of air through the upper portion of

the fixture; and in order to prevent the possibility of direct rays of light being visible or from passing out between the holder 17 and the lower part of cap 10, the latter is 5 preferably skirted or flared, as shown at 19, so as to depend below the attaching lugs 18 and therefore extend below the upper end of holder 17. By flaring the lower end of cap 10, as shown at 19, an intervening space 10 is provided for the passage of air.

The holder 17, in the construction shown in Fig. 1, like the cap 10, is made of cast metal and formed so as to provide the lower enlarged rim or flange portion 20 adapted to 15 receive the upper outwardly curled or turned top of the main reflector 21.

The main reflector 21 is preferably made of translucent material adapted to reflect downwardly, the direct rays of light issuing 20 from the lamp 16, as well as to diffuse the light above and to the sides of the fixture. The main reflector 21 is removably held in the holder 17 by means of suitable set-screws 22 of which any suitable number may 25 be employed, disposed circumferentially about the flare of the holder 17, as illustrated in Fig. 2.

The main reflector 21 is preferably made flaring toward its bottom as shown, so as 30 to extend a considerable distance beyond the sides of the globe 23.

The globe 23 is preferably formed of a single piece of glass with the lower portion made substantially semispherical or convex 35 and preferably coated with a diffusing enamel finish so as to be translucent; while the upper portion of the shade is preferably of clear glass and substantially bell-shaped providing a reverse curvature immediately above the lower globe portion.

The coated translucent surface of the inner concaved sides, disposed toward the lighting element of the lamp 16, in addition to diffusing the light, also reflects the rays of light 45 onto the main reflector 21.

The upper clear glass portion of globe 23 presents a convex surface toward and in close proximity to the lighting element of lamp 16, which produces an effect somewhat 50 similar to that of a lens, whereby the rays of light are converged toward the upper part of the main reflector 21; the main reflector 21 being either of opal or opaque glass, or provided with a coated translucent surface, 55 so as to both reflect and diffuse the rays of light.

The globe 23 is preferably removably held in place by means of the set-screws 24 which extend through the flange or rim portion 20 60 of the holder 17, as shown in Fig. 1, so as to be supported independently of main reflector member 21. Any suitable number of set-screws 24 may be employed; the set screws 24 being preferably circumferentially 65 disposed in a plane above that of the set-

screws 22 and therefore arranged above the upper portion of main reflector 21. The screws 24 take into the circumferential groove surrounding the upper part of globe 23, and are preferably arranged in an alternate relation with the set screws 22, as shown in Fig. 2.

Surrounding the upper or stem portion of the lamp 16, I provide an interior reflector 25, preferably of sheet metal having dished 75 sides so as to provide the concaved surface intermediate of the lower end and the upper attaching end; the interior reflector being somewhat in the nature of an inverted truncated cone. The interior reflector 25 is preferably so arranged that its upper end is substantially in the same plane as the top of main reflector 21, with the curvature of the sides of interior reflector 25 arranged to reflect the rays of light downwardly and outwardly in a diverging manner; the interior reflector 25 being preferably provided with a coating of white enamel.

The upper circumferential edge of the interior reflector 25 is shown curled or curved inwardly to provide the rim shown at 26 in Fig. 1, adapted to receive the free ends of the brackets 27, 27 which are secured by means of the screws 18 to the cap 10, namely the same screws which fasten the holder 17 95 to the cap 10.

The globe 23 is preferably provided with a ventilating opening 23^a in the bottom thereof to permit air to pass upwardly therethrough. The lamp 16 is preferably 100 so arranged as to bring its lighting element a slight distance beneath the juncture of the concaved clear glass portion and the convexed or rounded portion of globe 23 and therefor in the coated portion of the globe 105 so that no direct or undiffused rays of light may pass to the outside of the fixture.

With the construction shown in Fig. 1, it is apparent that a fixture or lighting unit is provided especially intended for semi-direct lighting whereby no direct rays of light can be discerned, as the translucent portion of the globe 23, namely the lower substantially semi-spherical portion of the globe, and the flare or depth of the main reflector, 115 as well as the lighting element of lamp 16, are so correlated that the lighting element of the lamp will not be visible. The construction or formation of the respective members, as well as the method of securing 120 them together, result in a fixture free from the objection found in the semi-direct lighting fixtures as heretofore constructed because of the unsightly shadows thrown on the ceiling and side walls, due to the construction and method of assembling, necessitating the employment, in such fixtures, of supporting rods or chains.

In Fig. 3 I show a modification of my invention wherein the cap 10^a, instead of be- 130

ing of cast metal, consists either of stamped or spun sheet metal; the cap being skirted or flared at the bottom, as shown at 19^a, illustrating in this respect another form; 5 the cap being bell-shape and thus providing an air-space intermediate of the reflector-holding portions of the fixture and the cap. The holder 17^a is also shown stamped or spun out of sheet metal and given slightly 10 different shape. Because of the thinness of the metal, the lower edge is turned or flanged inwardly as shown at 28, so as to retain or hold the comparatively thick band or ring 29 of suitable material, which is provided 15 with suitable tapped holes for the set-screws 22 and 24, whereby the main reflector 21 and the globe 23 are secured in place.

The upper end of holder 17^a is provided 20 with the inwardly presented and horizontally disposed circumferential flange 29^a about the central opening in the holder 17^a. This flange, at diametrically opposite points, is provided with sockets 30 of a width less than the width of the major portion of the 25 strap or yoke 31. At points coincident with the sockets 30, the strap or yoke 31, is cut away or notched on both edges of each leg of the yoke or strap 31, which permits the strap or yoke 31 to enter the sockets in the 30 flange 29 in the manner shown at 35 in Fig. 4.

The strap or yoke 31 is preferably made 35 of spring metal so that the side portions or legs of the yoke may be compressed and allowed to spring into the sockets 30; the yoke or strap, in so far as the construction just described is concerned, being identical with the strap or yoke 31^a shown in Fig. 4. The distance between the upper portions 40 of the legs of the strap or yoke is such as to permit the socket or lamp-holder 14 to be placed within the yoke so as to fit more or less firmly in place, and thus prevent improper contraction of the side portions of 45 the strap or yoke while the socket 14 is in place, so that the yoke or strap will be maintained in holding relation with reflector or globe holder 17^a.

The upper central portion of the yoke 31 50 is made sufficiently heavy or burred at the point 32 so as to permit the same to be tapped to receive the threaded end of the plug-portion of the attaching or suspending loop-member 33, which, in turn, is adapted 55 to receive the usual supporting chains or other suitable means. The plug or stem-portion of the attaching loop-member 33 is, of course, provided with an opening extending centrally therethrough for the passage of the electric wires which are secured 60 to the respective contact points or terminals in the socket 14.

The yoke or strap 31, on its sides slightly 65 beneath the top thereof, is shown stamped out so as to permit these portions to be bent

inwardly to provide the lugs 34, 34. The lugs 34, 34 are provided with threaded openings to receive the screws 15^a, 15^a whereby the socket 14 is secured in place.

The yoke 31, in Fig. 3, is shown partially 70 in section and partially in side elevation; and the lower ends of the yoke or strap 31 are bent outwardly to engage with the curled or inturned upper edge 26 of the interior reflector 25; reflector 25 being in the 75 nature of a band or shell so as to permit the neck-portion or stem of the lamp 16 to pass therethrough and be screwed into the socket 14. The interior reflector 25 is secured in place by springing the ends of the 80 yoke or strap 31 together, in order to permit the lower bent ends to spring or snap beneath the inturned or upper edge 26, as will be readily understood.

By providing the yoke or strap 31 with 85 the threaded opening at the top to receive the threaded stem or plug of the suspending member 33, it is evident that the cap 10^a will be firmly held in place when the loop-member 33 is screwed into the yoke, as 90 shown in Fig. 3; the yoke 31, in this construction, being made to carry the entire fixture or unit.

It will be understood, of course, that the fixture illustrated in Fig. 3 contemplates the 95 employment of a main reflector 21 and globe 23, constructed and arranged to provide the shadowless lighting effect obtained with the construction disclosed in Fig. 1.

In Fig. 4, I illustrate another modified 100 form of strap or yoke 31^a; the general construction of the yoke being similar to the yoke 31 shown in Fig. 3, except that the yoke 31^a is not stamped out so as to provide the lugs 34. The yoke 31^a is provided with 105 the slots or notched portions, as indicated at 35, similar to yoke 31 so as to permit the yoke to be sprung or forced into the grooves formed in the top flange 29 of the reflector or globe holder 17^a, as previously described. 110 As is clearly evident from the construction shown in Fig. 4, where a portion of the holder 17^a is broken away, so as to more clearly illustrate the relation between it and the yoke 31^a, displacement of the holder 17^a is 115 impossible with the yoke or strap 31^a in its normal expanded condition. The top of the yoke is provided with a threaded opening, like the yoke shown in Fig. 3, to receive a suitable attaching element, like the loop- 120 member 33 shown in Fig. 3. The lamp-holder or socket in this construction, is to be secured to the cross-member 36 by means of the usual screws which take into the tapped holes 37 in the cross-member 36 on 125 opposite sides of the central opening 38 through which the lead lines or electric wires pass.

The upper sides of the yoke or strap 31^a 130 are provided with the vertically disposed

elongated slots 39 for the passage of set-screws or members 40 which take into the upturned ends 41 of the cross-member 36. With this construction, it is evident that 5 the cross-member 36 may be raised or lowered, thereby raising or lowering the socket attached thereto and necessarily adjusting or affecting the relation of the lamp or lighting element to the coated portion of 10 the globe 23 and therefore also to the main reflector 21.

The construction shown in Fig. 4, like the construction shown in Fig. 3, contemplates the employment of a cap like the cap 15 10^a in Fig. 3, held in place by the strap or yoke 31^a and the suspending or attaching means adapted to screw into the tapped opening at 32; and the reflector or globe holder 17^a is also intended to support both 20 the main reflector 21 and the globe 23 as in the previously described constructions.

My invention, as herein shown and described, provides a lighting fixture or unit whereby the rays of light are diffused and 25 reflected in the most advantageous manner without producing objectionable shadows because of the formation and method of securing the elements or parts together; while at the same time the lamp or lighting 30 element is inclosed in a dust-proof globe which permits of ample ventilation therethrough and throughout the attaching portions or members of the fixture. In my improved constructions, the lamp, reflectors 35 and globe are all supported, directly or indirectly, by a single member of the fixture, to wit, either by the top cap, or by the strap or yoke; the lamp-receiving socket or holder being secured within the fixture; while the 40 light-receiving surfaces of the various members of the fixture are so formed and correlated that all direct rays of light will either be reflected or diffused and the lighting element made invisible.

45 I have shown and described what I believe to be the simplest and best forms of my invention, but the same may be altered in certain details without, however, departing from the spirit of my invention.

50 What I claim is:

1. In a fixture of the class described, a yoke of resilient metal provided with an opening in the top adapted to receive a suspending member, while the depending sides 55 at intermediate points are adapted to support a reflector-holding member when the yoke is in expanded condition, said yoke being provided with means transversely disposed in the upper part thereof intermediate of the sides for the attachment of an electric lamp socket, while the lower ends of the yoke-sides terminate in outwardly presented reflector-engaging portions.

60 2. In a fixture of the class described, a yoke formed so as to provide two depending

legs, the legs being formed to support a globe and reflector holding member while the lower ends of the legs are adapted to support a supplemental reflector, the upper portion of said yoke being provided with 70 means for securing an electric lamp-socket or holder between the legs of the yoke and arranged to permit the passage of the electric wires therethrough.

3. In a fixture of the class described, a 75 yoke of resilient material bent so as to provide two depending legs, the legs, at points intermediate of their ends, being arranged to support a globe and reflector holding member, while the lower ends of the legs 80 are formed to support a supplemental reflector, said yoke being adapted to receive an electric lamp-socket between the legs and formed to provide attaching points therefor, while the top or bowed portion of said yoke 85 is tapped to receive a supporting element.

4. In a fixture of the class described, the combination of a globe-holder and an inner reflector, with a U-shape holding member of resilient material adapted to support both 90 the globe-holder and said reflector, said holding member being provided with an opening in its top for the passage of electric wires and the means whereby the fixture is suspended in place, the member being also 95 provided with transversely disposed means between its side and adjacent the top thereof adapted to receive an electric lamp holder between the depending sides whereby the sides of said holding member are held distended and in supporting relation with said globe-holder and said inner reflector.

5. In a fixture of the class described, the combination of a lamp socket and a reflector-supporting member composed of a strip 105 of resilient metal bent substantially into U-shape and provided with an opening in its top to receive the fixture-suspending means and electric wires leading to the socket, the depending legs of said member being provided with supporting surfaces at points intermediate of the ends of the legs and at the lower ends thereof, with a globe and reflector-holding member provided with engaging surfaces correlated to the surfaces on the intermediate portions of the legs of said first mentioned supporting member, and a supplemental reflector provided with engaging surfaces adapted to be engaged by the supporting surfaces at the ends of the legs 115 of said first mentioned supporting member.

6. In combination with the globe and reflector holding member of a lighting fixture, an inverted U-shape resilient member adapted to pass through said globe and reflector-holding member and expand into holding engagement therewith, said resilient member being provided with lamp-socket attaching means adjacent the upper bowed portion thereof.

7. In a lighting fixture of the class described, the combination of a globe and reflector-holding member open at top and bottom and provided with an inwardly disposed flange about the open top, with an inverted U-shape resilient member adapted to pass through the open top of said holding member and form holding engagement with the flange of said holding member when the resilient member is in expanded condition, the upper bowed portion of said resilient member being provided with a tapped opening to receive a suspending element and to permit passage of electric wires there-through, said resilient member being provided with means intermediate of its side portions for the attachment of an electric lamp-holding socket.
8. In combination with a globe-holding member of a lighting fixture, an inverted U-shape resilient member adapted to pass through said globe-holding member and expanded into holding engagement therewith, said resilient member being provided with lamp-socket attaching means adjustably mounted between the side portions or legs adjacent the upper bowed portion of said resilient member. 20 25
